CIRCUIT BREAKER

Ralph H. Swingle, Pittsburgh, Pa., assignor to
Westinghouse Electric & Manufacturing Com-
pany, East Pittsburgh, Pa., a corporation of
Pennsylvania

Application September 29, 1934, Serial No. 746,255

22 Claims. (Cl. 175—294)

My invention relates generally to circuit interrupters and is particularly concerned with circuit breakers of the type used for controlling distribution feeder and lighting circuits.

In the past, it has been rather common practice to provide fuses or fuse and switch arrangements for protecting circuits of this type. These devices were not entirely satisfactory, however, due to the undesirable discontinuities of service which resulted when the fuses melted, and in addition, the arrangements were somewhat dangerous, particularly when it became necessary for an inexperienced individual to replace a blown fuse.

In order to obviate these difficulties, circuit breakers of suitable rating have been devised for use in protecting this type of circuits. Circuit breakers have numerous advantages over the older fuse or fuse and switch combinations: they are inherently safe, being capable of opening large amounts of power without serious or damaging arcing; and what is more important, they may be reclosed, after they have opened the circuit following the occurrence of an overload, by any person however inexperienced, without danger and without the inconvenience of securing a new fuse.

In the type of service under consideration, the load usually consists of lights, appliances, or small motor-operated devices. These devices frequently develop faults either in the internal insulation or in the insulation of the cords or other means used for connecting them into the circuit, a common example being the failure of an electric iron cord.

If such a fault occurs on a circuit which is protected by a fuse or a standard type circuit breaker the immediate result is to cause either the blowing of the fuse or the opening of the breaker.

All power is removed from the circuit and there is no way of determining exactly where the fault condition exists. Usually the housewife or operator of the machine, as the case may be, inserts another fuse without removing the faulty apparatus from the line, with the result that the fuse again blows or the circuit breaker again opens. The danger incident to the blowing of the fuse is, of course, obviated when a breaker is used, but even in this case it has been necessary to go to the point where the breaker is located and reclose it.

It would appear that the solution of the problem lies in the provision of a circuit breaker, suitable for use in circuits of the type under consideration, which will automatically open the

circuit so as to prevent damage to the line or supply equipment upon the occurrence of overloads or abnormal circuit conditions, and which will automatically reclose itself when and only when the fault conditions are removed from the controlled line, and to provide such a breaker is the principal object of my invention.

Another object of my invention is to provide a circuit breaker of this type which shall be provided with a movable operating member for permitting both manual and automatically controlled movement of the breaker contacts to the open or to the closed-circuit position.

A further object of my invention is to provide a circuit breaker of the type mentioned in the principal object which shall be simple and inexpensive to manufacture, and which shall be safe and reliable in operation.

A still further object of my invention is to provide a circuit breaker which shall be snap-acting in either direction, which shall open the controlled circuit upon the occurrence of excessive overloads or other abnormal conditions, irrespective of the position of the operating member, and which shall be provided with means for effecting the automatic reclosing of the contacts immediately following the removal of the over-load or abnormal conditions in the controlled circuit.

In carrying out these objects of my invention, I provide a circuit breaker which utilizes a snap-acting mechanism of the toggle-linkage and over-center spring type. The mechanism includes means for cooperating with an electro-responsive tripping element in order to effect the opening of the breaker upon the occurrence of overload or fault conditions, and in addition, it is provided with a magnetically responsive means for reclosing the contacts following each opening of the breaker, which results from the operation of the electro-responsive trip device, after the fault condition has been remedied.

In one form of my invention, the electrical circuit through the breaker is never entirely opened, but when the contacts are moved to the open-circuit position a current limiting impedance or a transformer is automatically inserted into the circuit in order to limit the amount of current which may flow in the controlled circuit. In another form, the contacts of the breaker are movable through three positions; the normal open and the normal closed-circuit position, to which the contacts may be moved by actuation of the operating member, and a tripped position to which the contacts are moved automatically

upon the operation of the electro-responsive means. Both of these forms include magnetic means, which are responsive to the conditions in the controlled circuit, for effecting automatic reclosing of the breaker mechanism.

- Through this arrangement, I provide a device which effectively protects the circuit from any damage which might result, due to an overload or other fault condition, and at the same time, 10 I provide a device which is automatically operable to restore the circuit to its normal condition immediately following the removal of the faulty apparatus or the like. Thus, when a defective piece of apparatus is connected into the circuit 15 16 the immediate effect is to produce an opening of the breaker and the limiting of the amount of current which may flow in the circuit. This condition becomes immediately apparent to the user by virtue of the extinguishment of the lights or 20 25 by the stopping of other equipment connected to the same line and all that is necessary for that person to do in order to restore the line to its normal energized condition is to remove the defective piece of equipment from the line by pulling out its attachment plug or turning off its switch, whereupon the breaker automatically restores itself to the normal position. The convenience of such an arrangement and its desirability, particularly when used in homes or 30 similar places, is apparent.

Another desirable feature which arises from my improved circuit breaker is that the location of faulty equipment is greatly facilitated, it being merely necessary, when investigating a faulty 35 circuit having a large number of pieces of connected equipment, to remove each piece successively, the removal of the faulty one immediately effecting the restoration of the circuits to its normal condition.

40 These and other objects of my invention will be made more apparent in the following description of a preferred embodiment of my invention.

Referring to the drawings:

45 Figure 1 is a sectional view of a single-pole, manually-operable circuit breaker which embodies the principal features of my invention;

50 Fig. 2 is a sectional view, similar to Fig. 1, showing the circuit breaker illustrated in that figure in the normal open-circuit position;

55 Fig. 3 is a sectional view, similar to Figs. 1 and 2, showing the circuit breaker in the tripped position;

Fig. 4 is a sectional view taken on the line 55 IV—IV of Fig. 1;

Fig. 5 is a fragmentary, perspective view showing certain of the details of the operating mechanism used in the breaker illustrated in Figs. 1 through 4;

60 Fig. 6 is an enlarged, fragmentary view of the operating mechanism shown in the other figures of the drawings at the instant just preceding the automatic reclosing of the contacts;

Fig. 7 is a sectional view taken on the line 65 VII—VII of Fig. 1;

Fig. 8 is a diagrammatic view of the electrical connections of the breaker shown in Figs. 1 through 7; and

70 Fig. 9 is a diagrammatic view of the electrical connections of a modified form of the breaker shown in the other figures of the drawings.

75 The circuit breaker mechanism is entirely supported upon a base 1 which is of molded insulating material, and includes three terminal members T₁, T₂, and T₃, a main stationary contact

3, a movable switch arm 5 for cooperating with the main stationary contact, an operating mechanism 7 for moving the switch arm 5 to the open and to the closed-circuit position, a solenoid means 9 for effecting the reclosing of the breaker, 5 and an electro-responsive element 11, which is adapted to cooperate with the operating mechanism 7 so as to effect the automatic opening of the breaker on the occurrence of predetermined conditions. A resistance, transformer, or other 10 impedance means 13 is likewise supported on the base 1, and is so connected in the electrical circuit through the breaker (see Fig. 8) that it limits the amount of current which may flow there-through during the existence of a fault or other 15 abnormal condition in the controlled circuit. The various structural elements of the device are enclosed by means of a suitable cover 15, likewise of molded insulating material, which is held in position on the base 1 by a screw 17. 20

The switch arm 5 comprises a U-shaped frame 19, having rearwardly extending portions 21, a spring support 23 for the movable contact 25 which engages the stationary contact 3 when the breaker is in the closed circuit position, and a flexible shunt 27 for connecting the support arm 23 with the terminal member T₂. The switch arm is pivotally supported through the agency of a pivot pin 31 upon a U-shaped frame 25 29 which is bolted to the base 1. 30

The operating mechanism 7 is supported upon a frame member 33 which is affixed to the base 1 by means of four cap screws 35. It includes a pair of toggle links 37 and 39, an operating member 41, and over-center spring 43 intermediate 35 the toggle links and the operating member, and a cradle 45 for so supporting the upper end of the toggle linkage that the operation of the bimetallic electro-responsive element 11 will cause the opening of the breaker, irrespective of the 40 position of the operating member 41.

The lower toggle link 37 has a bifurcated end portion which pivotally engages the frame 19 of the switch member 5 through the agency of a suitable pin 47. The upper portion of this link 45 is pivotally connected to the lower end of the other toggle link 39 by means of the knee pivot pin 49. This pin, as is shown particularly in Fig. 7, has a reduced portion 51 for engaging one end of the over-center spring 43. The upper end of 50 the toggle link 39 is pivotally fastened to the cradle member 45 by a pin 53, that member being, in turn pivotally supported on the frame 33 of the operating mechanism through the agency of a support pin 55. 55

The operating member 41 is pivotally supported on the main frame 33 by means of a pair of short pivot pins 57 which engage suitable openings in the U-shaped lower portion 59 of that member. A molded insulating member comprising a handle 60 portion 61 and a shield portion 63 is affixed to the closed end of the U-shaped portion of the operating member in order to permit manual movement thereof. The central portion of the U-shaped member 59 has a knife edge 65 (shown particularly in Figs. 5 and 6) formed integral therewith for engaging the upper end of the over-center operating spring 43. The molded handle portion 61 extends through an opening 62 in the cover 15 which opening is substantially closed at all times by the shield portion 63. The lower end of the right-hand side (Fig. 7) of the U-shaped portion 59 of the operating member is provided with a cam section 66 for effecting the reclosing of the breaker, as will be explained in some detail later. 70 75

A latch 67 is pivotally supported upon an arm 69 extending from one side of the main frame 33 and is biased in a counter-clockwise direction by means of a suitable coil spring 71. This latch 5 holds the movable contact 25 in the tripped position during the reclosing operation, in order that the deenergization of the magnetic reclosing means 9 shall not be affected before the entire mechanism has been restored to the normal 10 operative position.

The magnetic reclosing means 9 consists simply of a suitably supported attracting solenoid 73, a cooperating armature 75 and a link 77 for mechanically connecting the armature and the operating member 41. The particular design of the solenoid and armature is not an important part of my invention and any suitable arrangement may be used.

An auxiliary contact member 79 is supported upon the central tie portion 81 of the main operating frame 33, and this member is adapted to be engaged by the upper surface of the moving contact 25 when the breaker is in the tripped position. The auxiliary contact 79 is insulated from the frame 33 by means of a pair of insulating members 83 and is electrically connected to the attracting solenoid 73 of the magnetic reclosing means by means of a conductor 85. The other end of the attracting solenoid is electrically connected to the terminal T1 by a suitable conductor 87.

The bimetallic, thermally responsive element 11 is of U-shaped design such as is shown in Patent No. 1,802,758, issued to O. S. Jennings on April 28, 1931, and is rigidly supported on the base 1 of the interrupter by means of a pair of screws 89. The upper end of the element 11 terminates in an outwardly projecting metallic member 91 which is adapted to cooperate with the outer end 93 of the cradle 45, so as to restrain that member from moving under the influence of the biasing action of the over-center spring 43.

The electrical circuit for the preferred embodiment of my invention is shown schematically in Fig. 3. The terminal T1 is adapted to be connected to one side of the line and to one side of the load, and internally of the breaker, is connected to one end of the reclosing solenoid, as mentioned above. The other line is connected to the terminal T3, which in turn, is connected to one end of the current carrying, bimetallic thermally-responsive element 11 and by conductor 18 to one end of the current limiting resistance 13. The other end of the bimetallic element 11 is connected by conductor 12 to the stationary contact 3, and the other end of the resistance 13 is connected to the terminal T2. The switch arm 5 and the associated moving contact 25 are likewise connected by conductor 14 to the terminal T2.

From this it will be seen that when the breaker is in the open-circuit position the load is connected to the line through the current-limiting resistance 13. This resistance may, of course, be adjusted to any desired value.

When the breaker is in the closed-circuit position the load is directly connected to the line by means of the circuit through the terminal T2, the moving contact 25, the stationary contact 3, the bimetallic tripping element 11 and the terminal T3. It will be noted that the resistance 13 is short-circuited by the contacts and the bimetallic element 11.

When the breaker contacts are moved to the tripped position, as a result of the actuation of the bimetal, the reclosing solenoid 73 is connect-

ed directly across the load and the load is connected to the line through the current limiting resistance 13, the bimetallic element 11 being entirely removed from the circuit. So long as the fault or other abnormal condition exists on the load circuit, the voltage drop across the reclosing solenoid 73 will be very low and practically no current will flow therethrough. However, when the fault condition is removed from the load circuit, and the resistance of that circuit is returned to its normal value, the voltage drop across the reclosing solenoid 73 will be greatly increased, and by a proper selection of the coil and the resistance, may be caused to effect sufficient energization of the solenoid to make possible the reclosing of the breaker.

The operating mechanism 7 and the breaker contacts are shown in the closed-circuit position in Fig. 1. To open the contacts manually, the operating member 41 is moved in a clockwise direction, thereby bringing the line of action of the over-center spring 43 to the right of the line connecting the centers of the upper toggle link 39. As soon as this occurs, the mechanism reaches an unstable condition and the toggle linkage collapses to the position shown in Fig. 2, thereby effecting the opening of the breaker contacts with a snap-action. Movement of the switch arm toward the open-circuit position is definitely limited by the engagement of the projecting portion 95 of the upper toggle link 39 with the member 97 which connects the two side portions of the frame 33. The distances are so adjusted that the moving contact 25 does not engage the auxiliary contact 79 nor does it become latched-in when the switch arm moves to the open-circuit position due to movement of the operating handle.

To close the breaker manually after a manually produced opening operation, the operating member 41 is moved in a counter-clockwise direction from the position shown in Fig. 2, thereby bringing the line of action of the over-center spring 43 to the left of the line connecting the centers of the upper toggle link 39. This causes the contact arm to be moved to the closed position shown in Fig. 1 with a snap action. The circuit breaker of my invention may therefore be used as a snap-acting switch for normally opening and closing the circuit by manual operation of the handle.

When the breaker is in the closed-circuit position shown in Fig. 1 and an overload or other fault condition occurs in the controlled circuit, the excess current flowing through the bimetallic thermally responsive element 11 causes the upper end of that member to be moved so as to disengage the portion 91 from the outer end 93 of the cradle. When the breaker is in the closed-circuit position, the reaction forces of the over-center operating spring 43 bias the cradle 45 in a counter-clockwise direction, and as soon as the outer end 83 of that member is released by the bimetallic element, the cradle is free to rotate from the position shown in Fig. 1 to the position shown in Fig. 3.

This rotation takes place at high speed and effects a very rapid separation of the current-carrying contacts. In addition, as a result of the displacement of the toggle linkage which is effected by the rotation of the cradle 45, the stop 97 is not effective and the moving contact 25 moves in a clockwise direction until it engages the auxiliary contact 79 and simultaneously becomes latched against that contact by the latch member 67.

As pointed out above, the movement of the breaker mechanism to the tripped position in response to an overload serves to connect the reclosing solenoid 73 across the load and so long as the fault condition persists in the controlled circuit, the energization of that solenoid is insufficient to effect the reclosing of the breaker. However, as soon as the fault condition is removed, the armature 75 of the reclosing means is attracted toward the center of the solenoid 73 and the resulting movement causes the operating member 41 to rotate from the position shown in Fig. 3 to the position shown in Fig. 6. The latch 67 causes the contacts 25 and 19 to remain in engagement during this movement, thereby assuring that the solenoid will not be deenergized before the reclosing operation is complete.

As the operating member 41 is moved by the reclosing solenoid 73, the cam portion 66 of that member engages the edge of the bifurcated portion of the lower toggle link 37 (as shown particularly in Fig. 6) and causes that link to rotate in a clockwise direction. Since the switch arm 5 is prevented from moving by the latch 67 this rotation of the lower toggle link 37 is transmitted through the other toggle link 39 to the cradle member 45, causing that member to rotate in a clockwise direction. The surfaces of the cam portion 66 are so correlated with the other parts of the mechanism that the cradle member 45 is rotated to the normal closed-circuit position before the operating handle 41 has reached its limit of motion in the counter-clockwise direction, thus, shortly before the cam action is completed the end 93 of the cradle 45 is reengaged by the latching portion 91 of the electro-responsive element 44.

Very shortly after the cradle 45 is relatched, the latch 67 is released by the engagement of a projecting member 96 forming a part of the operating handle 41, with a suitable cooperating projection 98 formed integral with the latch itself. At this instant, the over-center spring 43 is tensioned so as to bias the toggle linkage toward the normal closed-circuit position, and immediately following the release of the switch arm 5 by the latch 67, the breaker moves to the closed-circuit position at high speed.

It will thus be seen that the reclosing operation not only recloses the breaker following (and only following) the removal of the fault or other abnormal condition from the controlled circuit, but at the same time, it restores the several parts of the operating mechanism to the normal operating position, thereby allowing the contacts to be moved to the open and to the closed-circuit position in the usual manner by movement of the operating member. The breaker is thus entirely automatic and substantially fool-proof.

It should also be noted that the circuit breaker distinguishes between an opening of the contacts manually by the handle and automatically in response to an overload. When the breaker is opened by manual movement of the handle, the reclosing solenoid is not connected in the circuit so that the breaker remains open, as was intended by the operation until it is again manually closed; but when the breaker is opened due to the flow of an excessive current, the reclosing solenoid is connected in the circuit and the breaker is automatically reclosed as soon as the condition causing the excessive current has been remedied.

For certain applications, it may be desirable that the electrical circuit through the breaker

shall be entirely opened when the contacts are in the normal open-circuit position. If this is necessary, it may readily be effected through the provision of a second auxiliary contact normally insulated from the first auxiliary contact but adapted to be connected to that contact when the breaker is in the tripped position. Such an arrangement is shown in Fig. 9, and it will be seen that this breaker differs from that previously described only through the addition of an extra contact member 181, to which the resistance 18 is connected. In this modified structure, the electrical circuit through the breaker is opened when the breaker is in the open-circuit position, and it is closed through the bimetallic electro-responsive element 44 when the breaker is in the closed-circuit position. When the breaker is in the tripped position, the electrical circuit is closed through the current limiting resistance or other impedance 18 and, as in the previously described structure, the reclosing solenoid 73 is directly in parallel with the load thereby assuring that the reclosing mechanism will not become operative until the overload or other fault condition is removed from the connected circuit.

From the foregoing, it will be seen that I have disclosed a new and improved form of circuit breaker which is particularly suitable for use with circuits which are frequently subjected to overload or other abnormal circuit conditions. My improved device includes the desirable feature that it is snap-acting in both directions for normally opening and closing the circuit, and that it is operable upon the occurrence of an overload or other abnormal circuit conditions to automatically open the circuit through the breaker, irrespective of the position of the operating handle, so as to prevent injury to the supply or other equipment. Further, my improved breaker includes means for automatically reclosing itself, and for restoring itself to a normal operative position, following each opening operation which results from the actuation of the electro-responsive means. Moreover, the automatic reclosing means is so designed that it will not effect the reclosing of the breaker until the fault condition is removed from the controlled circuit.

In addition to showing how a circuit breaker might be built embodying the above-described desirable features, I have shown how those features may be incorporated into a breaker similar to those in commercial use at the present time, thereby reducing the expense of embodying the features of my invention into commercial apparatus to a minimum.

While I have shown only a single-pole breaker, it is, of course, within the province of my invention that a multipole structure could be used, and it is obvious to one skilled in the art that numerous modifications and combinations of the invention may be worked out without departing from the broad principles disclosed. It is also possible, and probable, that various other forms of operating mechanisms may be utilized for accomplishing the objects of the invention. It is my intention, therefore, that the language of the accompanying claims shall be construed as covering such devices, and that my invention shall be limited only by what is expressly stated in those claims and by the prior art.

I claim the following as my invention:

1. In a circuit interrupter, separable contacts for opening and for closing the electrical circuit through said interrupter, actuating means for said separable contacts including an operating

member movable to normally cause said contacts to move either to the open or to the closed-circuit position, electro-responsive means operable upon the occurrence of predetermined conditions in the circuit to cause said actuating means to move said contacts to the open circuit position, and means operable only after said contacts have been moved to the open-circuit position as a result of the actuation of said electro-responsive means, for causing said actuating means to return said interrupter automatically to the closed-circuit position upon the removal of the cause of said predetermined conditions in the circuit.

2. In an automatically reclosing circuit breaker, contact means movable to an open and to a closed-circuit position, actuating means for said contact means including an operating member which is movable between two positions to cause said contact means to be moved to the open or to the closed-circuit position, electro-responsive means operable upon the occurrence of predetermined conditions in the circuit to cause said actuating means to move said contact means to the open-circuit position, and means for causing said actuating means to automatically reclose said contact means following each opening operation which is caused by said electro-responsive means, said means for causing automatic reclosing being inoperative during the existence of the cause of said predetermined conditions and when said contacts are moved to the open-circuit position by movement of said operating member.

3. In a circuit interrupter, contact means movable to an open and to a closed-circuit position, actuating means for said contact means including manually operable means for causing said contact means to be moved to the open or to the closed-circuit position, electro-responsive means operable upon the occurrence of predetermined conditions in the circuit to cause said actuating means to move said contact means to the open-circuit position independently of the position of said manually operable means, and means for causing said actuating means to automatically return said contact means to the closed-circuit position following each opening operation caused by the operation of said electro-responsive means, said means for causing automatic reclosing being operable only after those opening operations which are caused by said electro-responsive means and upon the removal of the cause of said predetermined conditions.

4. In a circuit interrupter, contact means movable to an open and to a closed-circuit position, actuating means for said contact means including an operating member which is movable between two positions to cause said contact means to be moved to the open or to the closed-circuit position, electro-responsive means operable upon the occurrence of an abnormal condition in the controlled circuit to cause said actuating means to move said contact means to the open-circuit position, and means for causing said actuating means to automatically return said contact means to the closed-circuit position following each opening operation which is caused by the operation of said electro-responsive means, said means for effecting the automatic reclosing of said interrupter being operable only after those opening operations which result from the operation of said electro-responsive means and, in addition, being operable only after the abnormal condition in the controlled circuit has been removed.

5. In a circuit interrupter, contact means moy-

able to an open and to a closed-circuit position, actuating means for said contact means including an operating member which is movable between two positions to cause said contact means to be moved to the open or to the closed-circuit position, electro-responsive means operable upon the occurrence of an abnormal condition in the controlled circuit to cause said actuating means to move said contact means to the open-circuit position independently of the position of said operating member, and means for causing said actuating means to automatically reclose said contact means following each opening operation which is caused by said electro-responsive means, said means for causing automatic reclosing being operable only when the abnormal condition is removed from the controlled circuit and, in addition, being operable only when the separation of said contact means has been caused by the operation of said electro-responsive means.

6. In a circuit interrupter, contact means movable to an open and to a closed-circuit position, actuating means for said contact means including an operating member which is movable to cause said contact means to be moved to both the open and the closed-circuit position with a snap action, electro-responsive means, operable upon the occurrence of predetermined conditions, to cause said actuating means to move said contact means to the open-circuit position likewise with a snap action, and means for causing said actuating means to return said contact means automatically to the closed-circuit position following each opening operation which is caused by the operation of said electro-responsive means, said means for effecting automatic reclosing of said interrupter being operable only after those opening operations which result from the operation of said electro-responsive means and, in addition, being operable only after said predetermined conditions have ceased to exist.

7. In a circuit interrupter, contact means movable to an open and to a closed-circuit position, actuating means for said contact means including an operating handle which is movable manually to cause said contact means to be moved to the open or to the closed-circuit position with a snap action, electro-responsive means, operable upon the occurrence of predetermined conditions, to cause said actuating means to move said contact means to the open-circuit position with a snap action independently of the position of said operating handle, and means for causing said actuating means to return said contact means automatically to the closed-circuit position following each opening operation which is caused by the operation of said electro-responsive means, said means for effecting automatic reclosing of said interrupter being operable only after those opening operations which result from the operation of said electro-responsive means and, in addition being operable only after said predetermined conditions have ceased to exist.

8. In a circuit interrupter, contact means movable to an open and to a closed-circuit position, actuating means for said contact means including an over-center spring means and an operating member, which is movable to cause said over-center spring means to move said contact means from one position to the other with a snap action, electro-responsive means operable upon the occurrence of predetermined conditions in the circuit to cause said actuating means to move said contact means to the open-circuit position, likewise with a snap action, and means for causing

said actuating means to return said contact means automatically to the closed-circuit position upon the removal of the cause of said predetermined condition following each opening operation which 5 is caused by the operation of said electro-responsive means.

9. In a circuit interrupter, contact means movable to an open and to a closed-circuit position, actuating means for said contact means, including 10 an over-center spring means, a toggle linkage, and an operating member, said operating member being movable to cause said contact means to be moved from one position to the other with a snap action, electro-responsive means operable upon the occurrence of predetermined conditions to cause said actuating means to move 15 said contacts to the open-circuit position, and means, which is operable only after said contacts have been moved to the open-circuit position as 20 a result of the actuation of said electro-responsive means, for causing said interrupter to return automatically to the closed-circuit position.

10. In a circuit interrupter, contact means movable to an open and to a closed-circuit position, actuating means for said contact means including 25 over-center spring means, and an operating handle, said operating handle being movable to cause said contact means to be moved from each position to the other with a snap 30 action, electro-responsive means operable upon the occurrence of an abnormal condition in the controlled circuit to cause said actuating means to move said contact means to the open-circuit position with a snap action independently of the 35 position of said operating handle, and means for causing said actuating means to return said contact means automatically to the closed-circuit position following each opening operation which is caused by the operation of said electro-responsive means, said means for effecting automatic reclosing of said interrupter being operable only 40 after those opening operations which result from the operation of said electro-responsive means and, in addition, being operable only after the 45 abnormal condition in the controlled circuit has been removed.

11. In a circuit interrupter, separable contacts for opening and for closing the electrical circuit through said interrupter, actuating means for 50 said separable contacts, including an operating member movable manually to cause said contacts to move both to the open and to the closed-circuit position, electro-responsive means operable upon the occurrence of predetermined conditions to cause said actuating means to move said contacts to the open-circuit position, and magnetic means which is energized in response to conditions in the circuit controlled by said interrupter for causing said actuating means to return said 55 interrupter automatically to the closed-circuit position following and only following each contact opening operation which is caused by said electro-responsive means.

12. In a circuit interrupter, contact means 60 movable between two positions, actuating means for said contact means including an operating member, a contact operating link, and an over-center spring intermediate said operating member and said contact operating link, said operating member being movable between two positions 65 to cause said contact operating link and said contact means to be moved from one position to the other with a snap action, electro-responsive means operable upon the occurrence of predetermined abnormal conditions to cause said actuat- 70

ing means to move said contact means to the open-circuit position, and magnetic means operable for causing said actuating means to return said contact means automatically to the closed-circuit position following and only following each 5 contact opening operation which is caused by said electro-responsive means.

13. In a circuit interrupter, contact means movable between an open and a closed-circuit position, actuating means for said contact means, including 10 an operating member, a toggle linkage, and an over-center spring intermediate said operating member and said toggle linkage, said operating member being movable between two positions to cause said contact means to be moved from one position to the other with a snap action, electro-responsive means operable upon the occurrence of predetermined abnormal conditions to cause said actuating means to move said contact means to the open-circuit position with a 15 snap action independently of the position of said operating member, and magnetic means for causing said actuating means to return said contact means automatically to the closed-circuit position following each opening operation which is 20 caused by said electro-responsive means, said means for effecting automatic reclosing being operable to effect the reclosing of said contact means only when the abnormal condition is removed from the controlled circuit and, in addition, being operable only when the separation of said contact means has been caused by the operation of said electro-responsive means.

14. In a circuit interrupter, a contact member movable to an open-circuit position, to a closed-circuit position, and to a tripped position different from said open-circuit position, actuating means for said contact means, including an operating member movable between two positions to cause said contact member to move to the open 40 and to the closed-circuit position, electro-responsive means operable upon the occurrence of predetermined abnormal conditions to cause said actuating means to move said contact member to the tripped position, and means operable only 45 when said contact member has been moved to the tripped position to cause said actuating means to return said contact member automatically to the closed-circuit position.

15. In a circuit interrupter, contact means, 50 actuating means therefor movable to an open-circuit position, to a closed-circuit position, and to a tripped position, said actuating means including an operating member movable to cause said contact means to move to the open and to the closed-circuit position, electro-responsive means operable upon the occurrence of predetermined abnormal conditions to cause said actuating means to move to the tripped position, and means for causing said actuating means to return 55 said contact means automatically to the closed-circuit position following each operation of the actuating means to tripped position, said means for effecting automatic reclosing of said contact means being operable only when said actuating 60 means have been moved to the tripped position, and in addition being operable only after the abnormal condition in the controlled circuit has been removed.

16. In a circuit interrupter, contact means, 70 actuating means therefor movable to an open-circuit position, to a closed-circuit position, and to a tripped position, said actuating means including snap-acting spring means and operating means manually movable to cause said contact 75

means to move to the open-circuit and to the closed-circuit position with a snap action, electro-responsive means operable upon the occurrence of a predetermined abnormal current condition in the circuit controlled by said interrupter to cause said actuating means to move to the tripped position and thereby cause said contact means to be moved out of the closed-circuit position irrespective of the position of said operating member, and magnetic means operable for causing said contact means to be returned automatically to the closed-circuit position following, and only following, each movement of said actuating means to the tripped position, said magnetic means being inoperative until the cause of said abnormal current condition has been removed.

17. In a circuit breaker, a movable contact member, an operating mechanism including an operating member movable between predetermined positions for operating said contact member to open and closed positions, a movable carrier for said operating mechanism, an electro-responsive element for releasably retaining said carrier in a latched position, said carrier being movable from the latched position to a tripped position in response to a predetermined abnormal current condition for causing said operating mechanism to move said contact member to a tripped position, electro-magnetic means operable when said contact member is in the tripped position for automatically actuating said operating mechanism to sequentially operate said carrier to its latched position and said contact member to its closed position, means for retaining said contact member in the tripped position until said carrier has been moved to its latched position, and current limiting means operative while said contact member is retained in the tripped position for causing a limited current to flow through the circuit, and said electro-magnetic means automatically actuating the operating mechanism in response to a predetermined change in said limited current.

18. In a circuit controlling device, separable contacts, actuating means for said separable contacts movable to open, closed and tripped positions, said actuating means including handle means for moving said contacts between open and closed positions, electro-responsive means operable upon the occurrence of predetermined conditions for causing said actuating means to be moved to the tripped position, impedance means connected in the circuit for causing a reduced current to flow through the device when in tripped position, and means responsive to a change in the flow of said reduced current through the device when said actuating means is in the tripped position only for automatically causing movement of said actuating means to the closed position.

19. In a circuit controlling device, separable contacts, actuating means for said separable contacts movable to open, closed and tripped positions, said actuating means including operating means for causing said contacts to normally open and close the electrical circuit through the device when moved to opened and closed positions respectively, electro-responsive means operable upon the occurrence of predetermined conditions

for causing said actuating means to be moved to the tripped position, means for causing a reduced current to flow through the circuit of the device when in tripped position, and means responsive to the flow of said reduced current through the device when said actuating means is in the tripped position only for automatically causing movement of said actuating means to the closed position, said last-named means causing movement of said actuating means to the closed position only upon the removal of said predetermined conditions.

20. In a circuit controlling device, a fixed contact, a movable contact, means for actuating said movable contact to open and closed positions with respect to said fixed contact, said movable contact also being movable by said actuating means to a tripped position, a second fixed contact adapted to cooperate with said movable contact to establish an electrical circuit through said movable and said second fixed contacts when the movable contact is in the tripped position, electro-responsive means operable upon the occurrence of predetermined conditions for causing said actuating means to move said movable contact to the tripped position, means connected in circuit only by said movement to tripped position for causing flow of current through the circuit controlled by the device, means for causing said actuating means to automatically move said movable contact from the tripped position to the closed position in response to a change in said current which flows when said movable contact is in tripped position.

21. In a circuit controlling device, contact means, actuating means including manually operable means for normally causing said contact means to open and close the circuit and electro-responsive means for causing said contact means to open the circuit upon the occurrence of a predetermined condition in the circuit, impedance means connected in shunt across said contact means when said contact means have been caused to open by said current responsive means for causing a reduced control current to flow in the circuit, means for causing opening of the circuit of said impedance means when said contact means is caused to open by said manually operable means, and means responsive to said reduced control current for causing reclosure of said contact means.

22. In a device for connecting a load to a line, main contact means by which said connection is made, actuating means including manually operable means for normally causing opening and closing of said main contact means and electro-responsive means for causing opening of said main contact means upon the occurrence of a predetermined condition, impedance means connected to the line side of said main contact means for causing a reduced control current to flow to the load when said main contact means have been caused to open by said current responsive means, means for disconnecting said impedance means from the line upon the opening of said main contact means by said manually operable means, and means responsive to said reduced control current for causing reclosure of said main contact means.

RALPH E. SWINGLE.
